UNITED STATES PATENT OFFICE.

HENRY P. CLAUSEN, OF MOUNT VERNON, NEW YORK, ASSIGNOR, BY MESNE ASSIGNMENTS, TO WESTERN ELECTRIC COMPANY, INCORPORATED, A CORPORATION OF NEW YORK.

CONNECTING-CIRCUIT FOR TELEPHONE SWITCHING SYSTEMS.

1,222,364.

Specification of Letters Patent.

Patented Apr. 10, 1917.

Application filed August 27, 1915. Serial No. 47,675.

To all whom it may concern:

Be it known that I, HENRY P. CLAUSEN, a citizen of the United States, residing at Mount Vernon, in the county of Westchester and State of New York, have invented certain new and useful Improvements in Connecting-Circuits for Telephone Switching Systems, of which the following is a full, clear, concise, and exact description.

10 This invention relates to connecting circuits for telephone switching systems of the manual type, and has for its object to provide means for assisting the operator in the supervision and control of such circuits.

15 In accordance with the general features of this invention, means are provided for giving the operator a warning signal in case of a premature disconnection of either end of a connecting circuit. The warning signal may

20 be in the form of a tone in the operator's telephone set. The tone may be given to the operator through the operation of the usual supervisory relays which are associated with the ordinary connecting circuit,

25 the only additional apparatus for carrying out this invention being the tone producing mechanism.

30 The accompanying drawing illustrates one of the organizations by which this invention may be effectuated.

In the drawing, subscribers' lines A and B are each connected by means of line wires 1 and 2 to a line jack 3 located at a central office. Included in each of these line circuits is the customary line relay 4 controlling line lamp 5 and a cut-off relay 6. At the central office there is provided an operator's cord circuit terminating in connecting plugs 7 and 11. Included in the talking

40 strands of each end of the cord circuit are the customary supervisory relays 8, 9 and 12, 13, the former of which conjointly controls the supervisory lamp 10, and the latter the supervisory lamp 14. Associated with the cord circuit is a circuit interrupting device 15 under the control of the operator by having its circuit include contacts of her listening key. The interrupting device 15 is adapted to produce a tone in the operator's head set when a circuit therefor is established. The actuation of either pair of the supervisory relays when the other pair is deenergized effects the closure of a circuit individual to a given pair of said relays for

the actuation of the interrupter 15. Ring- 55 current may be applied to a called line by means of a ringing key 28.

The operation of the apparatus in the drawing may best be understood by assuming that the subscribers' lines A and B have 60 been connected by means of the cord circuit. In such an event the supervisory relays 8 and 9 will have been energized over the following path: battery, coil of relay 8, ring strand of the plug 7 and jack 3 respectively, 65 line wire 1, through the substation A, back over line wire 2, tip strand of the jack 3 and plug 7 respectively, coil of relay 9, to ground. Likewise the energization of the supervisory relays 12 and 13 will have been 70 effected over the circuit which may be traced as follows: battery, coil of relay 12, ring strand and the plug 11 and jack 3 respectively, line wire 1, through substation B, back over line wire 2, tip strand of the jack 75 3 and plug 11 respectively, coil of relay 13, to ground. If the operator should inadvertently withdraw either of the plugs 7 or 11 from the jack associated with subscriber A or B, one pair or the other of the supervisory relays will be deenergized. We may 80 assume that the operator prematurely withdrew the answering plug 7. In this instance the supervisory relays 8, 9 will have been deenergized, while the supervisory relays 12, 85 13 will have been maintained energized. Under these conditions a circuit for the interrupter 15 will have been established over the following path: battery, interrupter 15, contact 16 of the operator's listening key, 90 conductors 17, 18, contact 19, conductor 20, contact 21, conductor 22, contact 23, conductor 24, contact 25, conductor 26, winding of induction coil 27, to ground. The operation of the interrupter 15 will produce a 95 warning tone or signal in the operator's head set and indicate to her that the withdrawing of the plug 7 was inopportune. This signal being given the instant she withdrew the plug 7, in many cases she may have 100 an opportunity of instantly reinserting the plug 7 in the jack of the calling subscriber's line, thus not seriously interrupting the conversation between subscribers A and B.

Now if we assume that the operator withdrew the calling plug 11 instead of the answering plug 7, the supervisory relays 12 and 13 would have been deenergized in this

case, while the supervisory relays 8, 9 would have remained energized. We will then have a second energizing circuit completed for the interrupter 15 which may be described as follows: battery, interrupter 15, contact 16, conductors 17, 30, contact 31, conductor 24, contact 32, conductor 33, contact 35, conductor 20, contact 36, conductors 37, 26, winding of induction coil 27, to ground. As stated before, the operation of the interrupter 15 produces a warning tone in the operator's head set and will indicate that she has accidentally removed the plug 11 from the jack of a busy line, and she can accordingly take any steps necessary to reëstablish conversation between subscribers A and B.

From the above it will be seen that by the means contemplated by this invention, an operator will be given a warning signal whenever she prematurely disconnects either one of the connecting plugs of her connecting circuit from a busy line. Upon receiving this signal she will be able in many cases to reëstablish the connection she inadvertently disturbed, without seriously discommuting or interrupting the conversing subscribers.

What is claimed is:

- 30 1. A telephone system comprising a pair of subscribers' lines terminating at a central office, a cord circuit connecting the lines together, a signaling device for the cord circuit, and an operating circuit for the signaling device controlled over one connected subscriber's line and completed by the disconnection of the cord circuit from the other line.
- 40 2. A telephone system comprising two telephone lines, a link circuit connecting the lines together, a signaling device for the link circuit, and an operating circuit for the signaling device controlled over one connected line and completed by the disconnection of the link circuit from the other line.
- 50 3. A telephone system comprising two subscribers' lines, a cord circuit connecting the lines together, a relay for each end of the cord circuit energized over the respective connected subscribers' lines, a tone producing device, and an energizing circuit for said device containing contacts of the relays.

Copies of this patent may be obtained for five cents each, by addressing the "Commissioner of Patents, Washington, D. C."

4. A telephone system comprising two telephone lines, a link circuit connecting the lines together, a tone producing device for the link circuit, and an energizing circuit for the tone producing device controlled over one connected line and completed by the disconnection of the link circuit from the other line.

5. A telephone system comprising two telephone lines, a link circuit connecting the lines together, a relay for each end of the link circuit energized over the respective connected lines, a tone producing device, and an energizing circuit for said device containing contacts of the relays.

6. In a telephone system, a pair of subscribers' lines terminating in line jacks at a central office, a cord circuit for connecting said lines together, a pair of supervisory relays for each end of said cord circuit, a tone producing device, and a plurality of energizing circuits for said device, the closure of a given one of said circuits being conditioned upon the energization of one pair of said relays and the deënergization of the other pair of said relays.

7. In a telephone system, a pair of subscribers' lines terminating in line jacks at a central office, a cord circuit for connecting said lines together, a pair of supervisory relays for each end of said cord circuit, a tone producing device, and a plurality of energizing circuits for said device, the closure of said circuits being controlled jointly by said relays acting in pairs.

8. In a telephone system, a pair of subscribers' lines terminating in line jacks at a central office, a cord circuit for connecting said lines together, a pair of supervisory relays for each end of said cord circuit, a tone producing device, and a plurality of energizing circuits for said device, said circuits being controlled collectively by said relays, one of said circuits being completed upon the premature withdrawal of one of the connecting plugs of said cord circuit, whereby the operator will be given a tone notifying her of said withdrawal.

In witness whereof, I hereunto subscribe my name this 18th day of August A. D., 1915.

HENRY P. CLAUSEN.
